METALWORKING MACHINE

Robert S. Brown, New Britain, and William B. Retz, Plainville, Conn., assignors to The New Britain-Gridley Machine Company, New Britain, Conn., a corporation of Connecticut

Application July 1, 1931, Serial No. 548,098

23 Claims. (Cl. 29—38)

Our invention relates to a metal working machine and will be described as embodied in a multiple spindle automatic chucking machine of the work rotating type.

5 It is the general object of the invention to provide a machine of the character indicated having improved structural and functional features, with a view to producing a high production machine, which is sturdy, having a high degree of 10 flexibility and safety in operation.

It is a more specific object to provide novel means for rigidly holding a turret or spindle carrier.

Another object is to provide a simplified form 15 of spindle drive combined with a tool slide feed means rendering the entire arrangement very compact.

It is another object to provide a machine having means to simplify assembly and disassembly 20 of the chucking mechanism and safety mechanism for the protection of an operator.

A still further object is to provide a safety device in connection with the chucking mechanism to avoid injury to the parts during opera- 25 tion.

Another object is to provide a novel and safe form of hand cranking mechanism.

A further object of importance is to provide an automatic work feed or magazine feed ar- 30 rangement having various safety features so as to avoid injury to parts of the machine and which is rapid and accurate in operation.

It is another object to provide a mechanism 35 for automatically rendering the feed works inoperative upon an abnormal functioning of parts of the machine, and incidentally in connection therewith, signal means for indicating normal as well as abnormal functioning.

Other objects and features of the invention will 40 either be pointed out or will become apparent upon a reading of the specification in connection with the drawings.

Briefly stated, the machine selected for em- 45 bodiment of the invention includes a frame hav- ing a spindle carrier or turret indexibly mounted thereon and carrying a plurality of spindles. Each spindle is provided with chucking mecha- nism, which, in the preferred form, is automatic- 50 ly actuated at the loading station. The tur- ret is rigidly held against end movement by an improved form of key or abutment mechanism, permitting free indexing but serving to rigidly hold the turret against end movement. The tur- 55 ret may be locked as usual by a locking bolt and may be clamped by a suitable clamping band

associated with the turret in a novel manner. Extending from the turret is a tool slide guide upon which a tool slide is movably mounted. The tool slide may be actuated by a draw rod extending through the turret, and the drive for the spindles is preferably concentrically arranged relatively to the draw rod, and the parts are so related as to save space and provide a compact machine. The tool slide may be adjusted on the draw rod with ease and nicety by means of an 10 improved adjustment which is provided. The chuck actuating devices may be very readily assembled and disassembled from the end of the machine, and there is a safety device to prevent accidental throwing in of the feed works while 15 parts are in position for assembly and disassembly. In connection with the form of chucking mechanism herein disclosed, we provide a safety device to prevent injury to the chuck upon an abnormal movement of a chucking rod which 20 is employed in the preferred form. The chucking is preferably automatically accomplished by cam means.

A magazine feed arrangement for automatically feeding work-pieces is so arranged as to pick 25 up a rough work-piece from the magazine and to simultaneously remove a finished work-piece from a chuck in loading position. The transfer member is then moved so as to place the rough work-piece in the chuck and to simultaneously 30 move the finished work-piece to a stripper from which the finished work-piece is removed to a suitable receptacle. The simultaneous functions performed by the transfer mechanism provides for accomplishment of all of the work feeding 35 functions in substantially half of the time required by a transfer device which must perform the functions above noted successively rather than simultaneously. The magazine feed and transfer arrangement is so arranged as to mini- 40 mize the danger of injury to any of the parts upon any abnormal functioning. Improved means preferably in the form of electrical contact means have been provided and arranged so that upon an abnormal functioning of the work feeding 45 means, the feed works will be thrown out, whereas, upon a normal functioning, the machine is designed to operate automatically and the operator need do nothing more than keep the magazine filled with rough work-pieces. A single op- 50 erator may therefore take care of the requirements of several machines. Upon an abnormal functioning, we preferably provide signal or tell- tale devices, such as a red light, to indicate a throwing out of the feed works, and we may 55

also provide a signal mechanism, such as a green light, to indicate the normal and desired functioning of the machine.

In the drawings which show, for illustrative purposes only, a preferred form of the invention embodied in a multiple spindle automatic chucking machine—

Fig. 1 is a view in front elevation of the left-hand portion of the machine;

Fig. 2 is a similar view of the middle portion of the machine and is substantially a continuation of Fig. 1;

Fig. 3 is a similar view of the right-hand portion of the machine and is substantially a continuation of Fig. 2;

Fig. 4 is a right-hand end view of the machine illustrated in Figs. 1, 2, and 3, parts such as cross slides being omitted;

Fig. 5 is an enlarged sectional view through the spindle carrier or turret and illustrating improved means for holding the turret against end movement and improved spindle carrier clamping means;

Fig. 16 is a sectional view of parts shown in Fig. 14;

Fig. 17 is a diagrammatic view illustrating the application of certain safety and signal means for the machine.

The general features of the machine, together with certain improvements, will first be described, and then the magazine feed mechanism, together with certain safety devices, will be taken up.

The machine, in general, comprises a sturdy frame 5 having the main driving motor 6 mounted thereon. The turret or spindle carrier 7 is indexably mounted in a substantially semi-circular bearing trough 8, whereby an extensive and very substantial bearing is provided over a consider-

able length of the spindle carrier and over approximately half of its circumference (Fig. 5). In order to very satisfactorily resist end movement of the spindle carrier under tool pressures, we provide key or abutment means intermediate the ends of the turret. As shown more particu-

larly in Fig. 5, one of the parts, such as the turret, is provided with a circumferential groove 9, while the other part (in this case the frame) is provided with a segmental key member 10 secured to the frame as by means of screws 11—11 and holding the same very rigidly therein. The key member 10 is preferably of a width to fit quite snugly in the circumferential groove 9, and when the tool pressures are transmitted to the spindle carrier, the key and groove arrangement forms a very secure and rigid support for the turret against endwise movement, and this without any outside plates or flanges.

The turret may be indexed in any suitable manner, such as by means of a Geneva or a gear mechanism (not shown). The turret may be locked in indexed positions as by means of a locking bolt 12 (Fig. 2), which may be spring pressed in the locking direction by means of a lever 13 and springs 14—14 and which may be positively withdrawn by means of the cam 15.

In addition to the locking bolt 12, we preferably provide a clamping band or strap 16 which may lie in the upper portion of the groove 9, though, as shown particularly in Fig. 6, it need not fill the groove. The clamping band 16 is preferably held at one end by an adjustable rod 17, and a spring 18 may be provided for urging that end of the clamping band 16 upwardly. To the opposite end of the band 16, an actuating or draw rod 19 is secured. A heavy spring 20 serves to urge the draw rod 19 downwardly, and thus the clamping band 16 is moved into clamping position. The clamping band 16 is positively moved to unclamp the turret as by means of a cam 21 and lever 22 engaging the lower end of the rod 19. Thus, the clamping band 16 is always moved into clamping position by a substantially uniform and predetermined force by means of the spring 20, and wear of the parts will not substantially change the clamping force. The clamping band is positively moved to its unclamped position. The upper or cap portion 23 of the frame serves as a cover for the spindle carrier and is preferably free thereof.

As heretofore indicated, the spindle carrier 7 is provided with a plurality of rotatable spindles 24—24, which may be mounted on preloaded ball bearings 25—25 (Fig. 6). Each spindle carries at its forward end a chuck designated generally 26 and shown on an enlarged scale in Fig. 6^a. As illustrated, each chuck comprises a housing or body 27 having a cam surface or cam surfaces 28 upon which ride chuck jaws 29—29. It will be seen that upon a rearward movement, that is, toward the right in Figs. 6 and 6^a of the jaws 29, the latter will be moved radially outwardly so as to grip a work-piece, such as the bearing ring 30, or other work-piece having a bore therein. In order to move the jaws 29 rearwardly to the gripping position, a stud 31 having a head 32 engages the jaws and is slidably mounted in the body 27. The stud 31 is preferably moved in the chucking direction by means of a draw rod 33 and heavy spring 34 as shown herein, but which chucking arrangement, by means of draw rod and spring and actuating means therefor, are claimed broadly in Brown application, Serial No. 276,590, filed May 10, 1928, now Patent 1,887,621, November 15, 1932.

In order to move the draw rod 33 against the heavy chucking spring 34 there is provided a yoke device 35 to engage the rear of the spindle or, more properly, an anti-friction device carried thereby, and the yoke 35 carries a push rod 36 in the form of a rack engaged by a pinion 37.

on shaft 38 mounted in the frame. The shaft 38 is rotated (Fig. 1) by means of an external lever 39 and link 40 on an actuating slide 41, which may be actuated by a cam and lever arrangement 42—43, as shown. Thus, upon movement of the slide 41 in one direction the pinion 37 will move the push rod 36 toward the left as viewed in Fig. 6, so as to compress a spring 34 and move the stud 31 through the instrumentality of a spring 44 which is interposed between the outside of a recessed head 45 and a flange 46 on the stud 31. In the interior of the recessed head 45 is an abutment head 47, which is secured as by means of a screw connection 48 to the stud 31. It will be seen that when the push rod 36 is released, as by movement of the slide 41, in the direction opposite to that last noted, the draw rod 33 will be forced rearwardly by the spring 34, and the shouldered head 47, being in engagement with the shoulder of the recessed head 45, will draw the stud 33 rearwardly so as to force the chuck jaws 49 outwardly into gripping position. Now, upon movement of the draw rod 33 toward the left, the recessed head 45 and spring 44 will force the stud 31 toward the left, to release the chuck jaws 29. Should the draw rod 33 be given more movement than is required for releasing the jaws 29, the head 47 may simply move rearwardly in the recessed head 45 and no damage to any of the parts of the chuck will result. In other words, the head 47 and recessed head 45 constitute a lost motion connection operable in one direction, so that the required movement of the draw rod 33 need not be so very accurately predetermined, and yet the jaws may be properly actuated.

In the form shown the spindle carrier 7 has centrally secured thereon a substantial tool slide stem 50, which may have a tapered fit thereon (Fig. 6) and be secured, as by means of a nut 51, threaded onto the rear end of the stem and engageable with a shoulder on the spindle carrier. The opposite end of the tool slide guide 50, as shown in Figs. 3, 4 and 8, is rotatably carried in a bearing 52 in the pedestal 53 on the frame of the machine. The tool slide 54 is slideable on the tool slide guide 50 and carries suitable tools, as will be understood. The tool slide 54 is guided and held against rotation during its feeding and return movements by means of a rigid arm 55, fitting in a longitudinal guideway 56 on the frame. The tool slide 54 is moved on its guide stem by means of a draw rod 57, adjustably secured at one end to the tool slide or an extension 58 thereof. The draw rod 57 extends through the guide 50, which is suitably bored for that purpose and extends to the left-hand end of the machine, where it is provided with a suitable cam follower 59, to be actuated on a cam on the main feed cam drum 60, as will be understood.

We have provided novel means for accurately adjusting the tool slide 54 on the draw rod 57 and for securing the same in adjusted position. In the form shown the tool slide 54 or, rather, the tail extension 58 thereof, is bored and counterbored to receive nuts 61—62 to engage opposite sides thereof. These nuts 61—62 are both threaded onto the end of the draw rod 57. Each of the nuts is provided with devices, such as gear teeth 63, and the tail extension 58 is longitudinally bored, as indicated at 64, so that a wrench in the form of a pinion may be passed thereto. By means of such a pinion wrench either

or both of the nuts may be engaged. With one of the nuts loosened up, both of the nuts may be rotated simultaneously so as to adjust the tool slide and draw rod 57 relatively to each other. When the proper adjustment has been made one of the nuts may then be turned up so as to very securely hold the draw rod to the tool slide. One of the nuts in effect serves as a lock nut for the other, and both nuts serve to effect adjustment.

A part of the spindle drive arrangement is of novel form and is so related to the tool slide draw rod 57 as to provide a compact and convenient arrangement. Fig. 6 shows more particularly the spindle drive works. A chain from the driving motor 6 (Fig. 1) serves to drive the sprocket 65 (Fig. 6) secured to the main drive shaft 66. The small gears 67 may be noted in passing as drive gears for a pump or pumps. The main drive shaft 66 passes to the left and secured thereon is a pick off gear 68 meshing with a second pick off gear 69 on a stub shaft. Pick off gear 69 is keyed to the gear 70 which in turn drives the gear 71 secured to the drive pinion 72, which in turn drives the gear 73. Gear 71 and pinion 72 may be fixedly mounted on a sleeve surrounding shaft 66 and free to rotate relatively thereto. By means of the pick off gears 68—69, any desirable spindle speeds may be secured.

In order to secure a concentric compact drive for all of the spindles, we provide a drive sleeve 74 which may be mounted on an anti-friction bearing 75 in the spindle carrier 7. A rear portion of the sleeve may be mounted on an anti-friction bearing 76 in the frame web 77. The drive sleeve carries a gear 78 meshed with and driven by the gear 73 which is driven by the pinion 72. The forward end of the sleeve 74 carries another gear 79 which is concentric with the spindle carrier and meshes with each of the spindle drive gears 80. Each spindle drive gear may be clutched and unclutched as by means of a clutch 81 from the spindle itself, and, if desired, a suitable brake may be engaged with a brake spool 82. In a chucking machine, each spindle when it reaches the loading position is normally unclutched from its drive so that the chuck may be loaded. The present concentric drive, however, may be employed in a screw machine. The novel driving arrangement including the drive sleeve 74 permits the passage of the draw rod 57 and may even act as a guide or support therefor if desired. The feed gear train is as follows:

During the normal feeding of the tools, the cam drive is from the drive pinion 72 (Fig. 6) to the drive gear 83 (Figs. 6 and 7). The drive gear 83 is rigidly connected by means of a sleeve to the gear 84 which meshes with a gear 85 keyed for rotation with a pick off gear 86. The gear 86 meshes with a second pick off gear 87 which drives one portion of an overrunning clutch 88, which in in turn drives the gear 89 through the shaft 90. The gear 89 meshes with and drives the gear 91 carried by a part of the main feed clutch designated generally 92. When the main feed clutch is in as indicated in Fig. 7, the sleeve 93 and pinion 94 are rotated and the latter meshes with the gear 95 which in turn drives gear 96. Gear 96, through the two gears 97—98 and gear 99, drives the main feed cam 69. The above described drive is for the slow traverse or working portion of the cam rotation.

An accelerated drive is provided for driving the cam shaft at a higher rate of speed during

the drawback, jump of the tools, indexing, spindle carrier locking, etc. The accelerated drive is from the main drive sprocket 65 and drive gear 108 (Fig. 6), which latter drives the gear 101 on the accelerated shaft 102 (Fig. 7). The gear 101 drives through a clutch 103, which in turn drives the shaft 90 and drive gear 89. The gear 89, by means of the gears 91, clutch 92 and gears 94 to 99 heretofore described, drives the main feed cam 60 at a rapid rate. This accelerated drive is permitted without unclutching the other gears heretofore described, because of the overrunning clutch 82, which permits the slow traverse gears to be driven in the usual manner and merely permits the gear 89 to run ahead of the normal drive of the slow traverse train. When the clutch 103 is out, the drive to the main feed cam 60 is through the slow traverse, and when the clutch 103 is in, the drive is through the accelerated gears or fast traverse. When the clutch 92 is out, it will be clear that there can be no drive to the main feed cam. As is usual in machines of this type, the clutch 103 is controlled by suitable dogs (not shown) on the main cam or some part coordinated therewith.

The main feed clutch 92 may be actuated manually by a handle 104 at the front of the machine, or a handle 105 at the rear of the machine. Both the handles 104—105 are suitably connected to a shaft 106 (Fig. 7) so that movement of either handle serves to rotate the shaft 106. The shaft 106 may carry a crank 107 connected by a link 108 to the clutch shaft lever 109, so that upon movement of either manual handle and consequent rotation of the shaft 106, the clutch 92 will be moved to either the "in" or the "out" position, as will be understood.

In connection with the main cam drive, we have provided a hand cranking mechanism (Fig. 40) 7) constituting an improved safety mechanism to render the hand cranking mechanism inoperative when the main feed clutch is in and which may automatically render the hand cranking mechanism operative when the main feed clutch is thrown out. In the form shown, the gear 98, which drives the feed cam gear 99, is carried upon a pinion sleeve shaft 110, and a rod 111 is splined to the shaft as by means of the teeth or splines 112. One end of the rod 111 is connected to the clutch shaft lever 109 so that when the latter is moved to throw the clutch in either direction, the rod 111 will be moved longitudinally and will always be splined to the cam driving sleeve shaft 110. There is a short sleeve or bushing 113 mounted in the frame and which is provided with teeth or parts 114 for coaction with the spline parts 112 on the rod 111. A shaft 115 is rotatable with the bushing 113, and, as illustrated, we have provided the shaft 115 with splines or teeth 116 which mesh with the complementary parts 114 in the bushing 113. A hand crank 117 is connected to the shaft 115 as by means of bevel gears 118. It will be clear that with the main feed clutch 92 in the "in" position as shown in Fig. 7, the rod 111 is positioned at the right-hand limit of its movement, and the splines or teeth 112 are withdrawn from the sleeve or bushing 113. However, when the clutch shift lever 109 is rotated so as to throw the clutch 92 out, the rod 111 is moved to the left so that the teeth 112—114 mesh with each other, and upon rotation of the hand crank 117, the rod 111, and through it the cam driving sleeve shaft 110, will be rotated so as to rotate the gear 98 for driving the main feed cam 60. Thus it is impossible to throw in the

hand cranking mechanism while the power feed is on, and by the mere act of throwing out the power feed by means of the main feed clutch 92 the hand cranking mechanism becomes operative.

There are other safety devices in connection with the main power feed clutch to prevent throwing in of the latter under certain conditions, as will be described. The machine is arranged so that a suitable bar or other tool may be inserted endwise to manually actuate the chucks in various stations. As shown more particularly in Figs. 6, 14, and 15, the frame is provided with a plurality of apertures 119—121—122—123 and a large aperture 124, each of these apertures being located in alignment with a spindle or chuck in various stations. These apertures are normally covered by a shiftable cover or annular plate 125 rotatably held to the frame as by means of a central disk 120 secured by screws 128. The cover or closure plate 125 is provided with means registering with the various apertures 119 to 124 when the cover plate is shifted to one position, and when shifted to another position, the cover plate serves to cover those apertures. As illustrated, the closure plate 125 has a large open notch 126 to register with the large apertures 124 in the frame, and is provided with smaller apertures 127—129—130. The closure plate may be further provided with an extended open notch 131 which permits access to the aperture 121 when shifted to one position. The notch 131 further permits the location of other parts on the frame, as will be later described.

Thus it will be seen that with the closure 125 in the position indicated in Figs. 6, 14 and 15, all of the frame apertures are covered. With the cover plate shifted clockwise, as viewed in Fig. 14, it will be seen that all of the frame apertures will be uncovered so as to permit access to the chuck actuating mechanisms. The various drive gears which may be in the way of a tool inserted through any of the frame apertures are preferably provided with spaced apart spokes, so as to readily admit a bar or other tool, as will be understood. The large aperture 124 is of sufficient size to permit removal or insertion of the chucking spring 38 and actuating rod 33 and other assembled parts.

The frame and cover plate 125 may further be provided with registering apertures 132—133, which are in registry with each other when the remaining openings in the frame and closure plate are out of registry and the frame openings therefore closed. Passing through the opening 132 is a rod 134 (Figs. 6, 14), which may be spring pressed inwardly by means of a spring 135. The rod 134 extends within the frame and is located in the path of a crank arm 136, carried by the shaft 106, which is oscillated for moving the main feed clutch 92. Thus, when the closure plate 125 is moved so as to uncover the frame openings 119 to 124, the openings 132 and 133 will be out of registry, and, by reason of the crank 136 and rod 134, it will be impossible to oscillate the shaft 106 and the main feed clutch 92 cannot be thrown in. By the means just described it will be clear that any tool inserted through the frame openings will have to be withdrawn and the cover plate 125 shifted so as to close all the frame openings before the main feed clutch can be thrown in. The rod 134, as will be later described in connection with certain electrical devices, is made use of for closing a normally open

switch when the clutch is thrown out, so as to energize a signal device.

Magazine feed

5 We have devised an improved and very rapid method of automatically feeding work-pieces to the chucks and removing the same therefrom. We have also devised certain safeguards and tell-tale devices to prevent injury to the machine 10 and to provide a check on its operation.

We may employ a magazine arrangement in the form of spaced plates 131-137 carried on an endless chain running over sprockets carried at the top of the frame. Beneath the lower run 15 of the chain is a slideway which, in the form shown, consists of a pair of bars 138-139 so that work-pieces such as bearing rings, for example, 140 may be placed by the operator between adjacent spaced plates 131-137 and may rest on 20 the two rods 138-139 and be slid therealong during movement of the chain. As will be later described, the chain is given a step by step movement so as to discharge a work-piece 140 at the proper time. As shown best in Figs. 4 and 9, 25 the work-pieces, shown as bearing rings, are moved along the guide rods 138-139, and when a work-piece reaches the proper location it moves down by gravity to the position indicated in Fig. 4. In order to permit this action, the guide rod 30 139 terminates just before the point at which it is desired to discharge a ring into a suitable holding device, and therefore when the ring passes beyond the end of the rod 139, it simply rolls or slides out from between its holding plates 137 and 35 moves down the adjustable guide track 141 and into engagement with a second adjustable guide or stop 142 where it reposes as is indicated particularly in Fig. 4. The guides 141-142 are so positioned as to quite accurately locate the ring 40 in any desired position to be picked up by a transfer device to be described.

In our preferred form, the transfer device is designed to pick up a rough work-piece from the holding device 141-142, and at the same time 45 pick out a finished work-piece from the chuck 26 in loading position and then transfer the rough work-piece to the chuck 26 in loading position and at the same time transfer the finished work-piece from the chuck 26 to a stripping device and thereafter move away to permit indexing of the spindle carrier. In the form illustrated, our transfer device includes two transfer chucks 143-144 carried by a transfer arm device 145 on a rotatable and longitudinally slidable shaft 146 mounted in the frame.

Figs. 11, 12, and 13 illustrate different forms of transfer chucks which may be employed. In the form shown in Fig. 11, external gripping jaws 147-148 are provided and are moved in the gripping direction by means of a spring 149 and draw rod 150. The forward ends of the jaws may be beveled as indicated at 150 so that by a mere longitudinal pressure on the transfer chuck, the work-piece, such as the ring shown in Fig. 11, 55 will expand the jaws and will be held between the jaws by the spring 148. Fig. 12 indicates a slightly different form of transfer chuck for internal gripping and consists of a sleeve having apertures therein for ball jaws 151 which are 60 spring pressed outwardly by means of the cone 152 and spring 153. Spring pressed plungers 154 may be provided for serving as a resilient backing for the work-piece. Fig. 13 shows still another form of internal gripping transfer chuck 65 70 in which the jaws 155 are pivoted somewhat like

those shown in Fig. 11 and are provided with tapered ends 156 so as to be automatically moved inwardly by the work-piece and against the spring 157. Fig. 13 illustrates, in addition, a pair of stripping fingers, to be later described. It is to 5 be understood that for various types of work, various appropriate types of transfer chucks would be employed.

The transfer chucks on the transfer arm 145 are spaced apart a distance equal to the distance 10 between the chuck 26 in the loading station and the work piece 140 (Fig. 4), the location of which for convenience we shall term the magazine, since the work positioning means is, in fact, a part of the magazine arrangement. The space between 15 the transfer chucks 143-144 is also equal to the distance between the chuck 26 in loading station and the stripping device, designated generally 159, and which may comprise a pair of spring pressed stripping jaws 160-160 (Figs. 2, 9 and 20 13), having tapered noses 161-161 to be engaged by the work piece and having shoulders 162-162 to engage behind the work piece so that, upon withdrawal of the transfer chuck, the work piece 25 will be stripped and fall into a suitable hopper.

Movements of the transfer arm 145 and transfer chucks carried thereby consist of a longitudinal movement inwardly to pick up a rough work piece from the magazine and at the same time pick up a finished work piece from the chuck in loading position. Transfer chucks are next moved outwardly and then rotatably, so as to bring the rough work piece opposite the chuck in loading position and the finished work piece opposite the stripping device. The transfer arm is then again moved longitudinally inwardly so as to position the rough work piece in the chuck in loading position and the finished work piece in the stripper. The chuck is then closed automatically to grip the work piece therein and the transfer 40 chucks are then again moved longitudinally outwardly to strip the finished work piece and leave the rough work piece in the machine chuck, after which the transfer device is again rotated upwardly to the initial position. These movements 45 are accomplished as follows:

As shown particularly in Figs. 2, 10 and 10^a, the transfer arm shaft 146 is journaled and slidable in spaced apart frame bearings 163-164. The shaft 146 is moved toward the right as viewed 50 in the drawings by positive means, such as the lever 165, having a nose 166 to engage a plug or button 167 secured in the end of the hollow shaft 146. A link 168 is pivotally connected at one end of the lever 165, and at the opposite end to 55 a bell crank lever 169, actuated in one direction by a cam 170 on the cam shaft. Thus, when the cam rocks the lever 169 so as to draw down on the link 168, the nose 166 in engagement with the button 167 positively moves the shaft 146 to the right, that is, in the direction to move the transfer chucks away from the magazine and machine chuck, which movement, as stated, removes a rough work piece from the machine chuck. After 60 the shaft 146 has been rotated by means to be described the shaft 146 is moved toward the left, so as to position the work pieces carried by the transfer chucks in the machine chuck and stripper. This left-hand movement is preferably 65 accomplished by spring means, so as to avoid injury to parts in case anything goes wrong with the machine.

In the form illustrated, a coil spring is located 70 within the hollow shaft 146 and is sustained at one 75

end by the button 167 and at the other end by a plug 171 having a pin therethrough forming gudgeons 172, held in a ring 173 which may abut a part of the frame, as shown particularly in Fig. 10. It will be clear that when the cam 178 permits, the shaft 146 will be resiliently moved to the left by the compression spring 174 and the link 168 will be raised to the position of Fig. 2.

The shaft 146 carrying the transfer mechanism is rotated by means, preferably including a cam and springs acting against limit stops. In the form illustrated, the shaft 146 has a long faced pinion 175 secured thereon (Figs. 2 and 10). A rack bar 176 is slidably guided in a bearing 177 on the frame and meshes with the pinion 175, so that upon movement of the rack bar 176 the shaft 146 and parts carried thereby will be rotated. A groove cam 178 (Figs. 2 and 4) serves to reciprocate the rack bar 176 through a connecting rod 179, and springs 180-181 preferably form part of the connecting means between the connecting rod 179 and the rack bar 176, as clearly appears in Fig. 2 and as will be understood. Needless to say, the cams 170 and 178 are of such form and are so located as to rotate the transfer arm and to move the same longitudinally at the proper times and in the proper sequence.

The operation of the transfer mechanism is as follows:

Assuming the transfer mechanism to be in the position indicated in Figs. 2 and 4, it will be seen that the cam 178 has raised the connecting rod 179 and through the spring 181 has moved the rack bar 176 upwardly to rotate the shaft 146, so as to bring one transfer chuck into alignment with the stripper mechanism 159 and the other transfer chuck into alignment with the machine chuck 26 in the loading station. The spring 174 in shaft 146 has served to rock the lever 165 and raise the link 168 so as to permit the shaft 146 and consequently the transfer chucks to move toward the left, that is, so as to convey the rough work-piece in the transfer chuck 143 into the machine chuck 26 in loading station and to bring a finished work-piece from the machine chuck 26 into the stripper 159. The spring connection between the rack bar 176 and the cam 178 has caused the transfer arm to be resiliently moved, until a guide block 182 (Fig. 9) contacted with the lower limit stop 183 adjustably secured on the machine frame. As stated, the spacing of the transfer chucks on the arm is such that when the limit stop 183 is engaged by the block 182, the work-pieces in the transfer chucks will be properly aligned with the machine chuck and the stripper.

Now upon movement of the cam 170, the lever 169 will be rocked so as to draw the link 168 downwardly and cause the nose 166 of the upper crank to positively shift the shaft 146 and transfer chucks toward the right, which movement serves to leave the finished work-piece in the stripper 159 and leave a rough work-piece in the chuck 26, it being understood that before this movement takes place the chuck 26 has been automatically closed by the means heretofore described. When the transfer chucks are free of the machine chuck and stripper they are so held free by a suitable dwell on cam 170, and the cam 178 then acts to draw downwardly on the connecting rod 179 and through the spring connection 180 the rack bar 176 is moved downwardly, so as to rock the shaft 146 and the transfer arm 145 into the rotative position shown in Fig. 9, which movement will bring the upper guide block

182 into engagement with the upper limit stop 183 adjustably secured on the frame. The arm 145 is provided with a shorter guide block 184, which short guide block permits the transfer arm 145 to swing into the position indicated in Fig. 9 when the shaft 146 is out the limit of its out movement. While the arm 145 is thus held in the position shown in Fig. 9 by the cam 178 and resilient connection heretofore described, the spring 174 slides the shaft 146 inwardly and resiliently moves the transfer chucks to the in position shown in Fig. 2. During this movement the lever 165, link 168, and lever 169 are moved to the positions shown in Fig. 2.

With the parts in the positions of Fig. 2 the transfer chuck 143 will pick up a rough work piece which has previously been dropped into the magazine positioning means 141-142 by means to be described, and the chuck 144 will at the same time pick up a finished work piece from the machine chuck 26 in loading position, which machine chuck is then automatically opened. During this in movement the transfer arm 145 is accurately guided by the two upper guide blocks 182-184, which will be in engagement with opposite sides of the limit stop 183, so as to accurately guide the transfer arm. The cam 170, through lever 169, link 168 and lever 165, will then positively move the shaft 146 and transfer arm to the right, so as to carry a rough work piece in the transfer chuck 143 and a finished work piece in the transfer chuck 144. During this longitudinal movement the short guide block 184 will pass beyond the end of the upper limit stop 183, and thereafter the cam 178, through the means heretofore described, will again rock the shaft 146, to move the transfer mechanism to the position indicated in Fig. 4, after which the cam 170 again permits the coil spring 174 to resiliently move the shaft 146 to the in position, so as to deposit a rough work piece in the machine chuck and enter the finished work piece in the stripper, as heretofore described.

Thus, in the time ordinarily required for removing a finished work piece from the machine chuck and conducting the same to a stripper, our transfer mechanism in addition picks up a rough work piece and transfers the same to the chuck. Considerable time is thus saved.

By the use of two transfer chucks instead of one, we not only save time but assure greater positiveness of action. One chuck which transfers rough work pieces is of appropriate size and design to properly grip surfaces on the rough work pieces, while the other chuck is of appropriate size and design to properly grip finished or other surfaces, on the finished work pieces. Thus, with each chuck designed to perform its single function, there will be greater certainty of action than where one chuck must handle both rough and finished pieces.

The chain portion of the magazine feed mechanism is moved in proper time with the transfer mechanism and is preferably moved by the same means that moves a part of the transfer mechanism. In the form shown (Figs. 2, 9) the shaft 125 of the inner sprocket for the chain is provided with a ratchet wheel 186, to be engaged and rotated by a pawl 187. The pawl is mounted upon a lever 188, which connects to one end of a link 189, the opposite end of which is connected to a bell crank lever 190, which in turn is connected by means of a link 191 to the rack bar 176 heretofore described. In order to determine the number of teeth on the ratchet wheel 186 to be 75

picked up by the pawl 187 at each actuation thereof, we preferably provide a knock-off plate 192, which may be pivotally mounted on the shaft 185 and adjustably held as by means of a pin and slot connection 193 to the frame. The pawl 187 is provided with a pin 194 which, during actuation of the lever 188, rides up on a cam surface 195 on the plate 192, and thus causes the nose of the pawl to be withdrawn from the 10 ratchet teeth and to prevent engagement of the nose of the pawl with another ratchet tooth until, by reverse actuation of the lever 188, the pin 194 is disengaged from the cam surface 195. Thus, by shifting the plate 192 and holding the same 15 in adjusted position by means of the pin and slot connection 193, the pawl may be caused to pick up one, two, three or any desired number of teeth at each actuation, so as to cause a new work piece to be dropped into the magazine 20 positioning arrangement 141-142 during each cycle. The magazine chain is thus actuated by the rack bar 176, so that a new work piece is dropped into the magazine positioning arrangement 141-142 at the time that the transfer arms 25 are in their out position and during rotation of the transfer arm in a downward direction, so that, when the transfer arm is again moved to the upper position as shown in Fig. 9, a new work piece will have been previously deposited and 30 will be ready to be picked up by the transfer chuck 143.

The resilient in movement of the transfer arm by the coil spring 174 prevents injury to the parts which might be occasioned were such movement positive and work-pieces or the like should jam in the chuck or magazine device. The resilient actuating means 189-191 likewise prevents injury to parts of the machine should there be any jamming action, and also obviates the necessity 35 for very accurate positioning or camming of the parts, since the transfer arm is moved up against limit stops. Thus, the same cams will take care of work pieces of different sizes and different shapes and transfer chucks of different 40 appropriate sizes, and, since the limit stops are adjustable, the transfer and magazine arrangements are exceedingly flexible.

In connection with the magazine loading device, we prefer to provide additional safeguards 45 and telltale devices for automatically stopping the machine as by throwing out the feed clutch and at the same time providing a signal to indicate that the feed clutch has been thrown out whenever there is an abnormal action to the 50 machine. We preferably also provide signal means in the form of a light to indicate that the machine is operating normally. In the form shown, we provide means for throwing the feed clutch in the event that the transfer chucks are 55 prevented from moving up to the magazine device and the machine chuck or stripper, or in the event that for any reason they do not move to the normal extent. We may likewise provide means for throwing out the feed clutch in case 60 the transfer chuck fails to pick up a work-piece, which failure might be due to a failure of the operator to load the magazine or to failure of some part of the machine preventing such pick 65 up.

70 Referring particularly to the diagrammatic drawing of Fig. 17, and to Figs. 2, 9, 14, and 15, it will be seen that we provide a solenoid 200 having a core piece 201 which periodically during normal operation of the machine is energized and serves 75 to prevent the feed clutch from being thrown

out. However, upon an abnormal operation of the machine, the solenoid 200 is not energized, and the feed clutch is thrown out mechanically. The main feed cam 90, or any auxiliary cam synchronized therewith, is provided with one or 5 more cam dogs 202, and in the path of these dogs is a cam roller 203 carried by a lever arm 204. The lever arm in the form shown is on a sleeve 205 loosely mounted on the shaft 106 between a fixed collar 206 and a fixed hub 207 carrying 10 a lever arm 208 which is ultimately connected to a manual handle at the front of the machine, as will be described. It will be recalled that the shaft 106, as appears more clearly in Fig. 7, controls the position of the main feed clutch 92 so 15 that upon oscillation of the shaft 106 that main feed clutch is thrown in or out. Splined to the sleeve 205 and slidably thereon is a sleeve or hub 209 which has means such as a pin 210 which is in the path of an ear 211 on the hub 207, 20 which, as stated, is fixed to the shaft 106. A spring 212 normally holds the pin in the positions shown in Figs. 15 and 16 so as to be in the path of the ear 211. It will therefore be seen that with the pin engaged behind the ear 211, as 25 shown, when the cam roller 203 is engaged by a dog, such as 202, the arm 204 and with it the sleeve 205 will be rocked in a clockwise direction as viewed in Fig. 15. This rocking will cause the pin behind the ear 211 to rock the hub 207 30 and with it the shaft 106, which, as has been described, will throw out the main feed clutch and the feed functions of the machine will be stopped until the clutch is again thrown in manually. As indicated in Fig. 15, a coil spring 213 35 serves to urge the lever 204 into the position shown so as to position the roller 203 in the path of the dogs such as 202, and each time a dog passes the roller, the arm 204 is rocked.

Now, when all parts of the machine are functioning properly, it is not desired to have the main feed clutch thrown out each time the lever 204 is rocked by a dog 202, and the solenoid core 201 is made use of for withdrawing the pin 210 from behind the ear 211 so that rocking of the 40 lever 204 will be a mere idle rocking movement and will not throw out the feed clutch. In the form shown, the sleeve or hub 209 carrying the pin 210 is engaged by a fork on a lever 214 fixedly carried by a shaft 215 mounted in the frame. 45 Also fixedly carried by the shaft 215 is an arm 216 which is connected by means of a link 217 to the core 201 of the solenoid. It will be clear that when the solenoid is energized to draw the core 201 inwardly, the shaft 215 will be rocked so as 50 to rock the fork 214 and withdraw the hub 209 and with it the pin out from behind the ear 211 so that a rocking of the arm 204 by the dog 202 will have no effect on the feed clutch. As soon 55 as the solenoid is de-energized, as will be later 60 described, the spring 212 again moves the hub 209 and pin 210 into the positions shown in Figs. 15 and 16 so that they are in position for clutch throwing.

The main feed clutch 92, in addition to being 65 movable by means of the manual handle 105 at the rear of the machine, is movable by the handle 104 at the front of the machine through a link 218, rock lever 219, link 220 and arm 208 on the hub 207. Thus, the main feed clutch may be actuated 70 manually from either the front or rear of the machine and may be automatically actuated by means of the pin and ear device heretofore described.

The electrical connections and devices for caus- 75

ing the solenoid 200 to be energized are shown more particularly in Fig. 17. We may provide line wires 225—226 and the main feed switch 227. A step down transformer 228 acts to reduce the voltage, and the low voltage current acts through a relay 229, for a purpose to be described. The link member 168 (Figs. 2, 17) which serves to positively move the transfer chucks outwardly, and which is itself moved upwardly by means of the coil spring 174 (Fig. 10) to resiliently move the chuck and transfer chucks inwardly, is provided with a contact 230 which is grounded through the machine. The machine frame carries an insulated contact 231 to be engaged by the contact 230 when the link 168 is moved to its predetermined upper position by means of the spring 174, as described. The contact 231 is connected by a wire 232 to a contact 233, which is engagable by a movable contact 234, movable by a dog 235 on what may be termed a distributor 236, forming a part of or movable with the main cam shaft. When the contact 230 is moved into engagement with the contact 231, there will be a flow from the ground connection through contacts 230—231, line 232, contacts 233—234 (when closed), thence through line 237 to actuate the relay and close the relay switch 238. When the relay switch 238 is thus closed, it will be clear that line current may flow through line 225, solenoid line 239, through the solenoid, then solenoid line 240, line 241, through the closed relay switch 238, and finally back through main line 226. When the solenoid is thus energized, the core 201 is drawn in and, as heretofore described particularly in connection with Figs. 15 and 16, the pin 210 is withdrawn from behind the ear 211, and rocking of the lever 204 by the dog 202 will have no effect on the main feed clutch.

If, for any reason, such as a jamming of parts, the rod 168 is not raised by the spring 174 so as to close the contacts 230—231, the relay 229 will not be energized, and the solenoid will not withdraw the pin 210 from behind the ear, and the feed clutch will be thrown out.

We preferably provide other safety devices, one of which is indicated particularly in Figs. 9 and 17. A movable contact member 242 grounded to the frame is pivotally mounted thereon at 243 and is spring pressed outwardly to the position shown in Figs. 9 and 17. An insulated contact 244 is mounted on a spring arm 245 on the frame in position to be engaged by the grounded contact 242. The contact 242 is positioned in the path of movement of a work-piece in a transfer chuck while the same is being transferred from the magazine positioning device 141—142 down to the position to be entered in the main machine chuck. In other words, each time a rough work-piece from the magazine is moved down by the transfer arm 145 it wipes along the contact 242 and closes the contacts 242, 244, so that, as shown in Fig. 17, current may flow from the grounded contact 242, contact 244, line 246, through the relay back to ground, so as to energize the relay and close relay switch 238, which closing, as heretofore described, permits line current to flow through the solenoid for drawing the core in and withdrawing the pin 210 from behind the ear 211, thus preventing the feed clutch from being thrown out by the dog 202 on the main cam.

If a transfer chuck should come down empty from the magazine, which might be occasioned by the failure of an operator to place work pieces in the magazine chain arrangement or which might be occasioned by some failure of the transfer

chuck to pick up a rough work piece, which latter condition might entail difficulties in having work pieces ball up in the magazine positioning device or chuck, there would be no wiping of the contact 242, and the contacts 242, 244 would remain open and the solenoid would not be energized as heretofore described. If the solenoid is not energized, the feed clutch will be thrown out by the means heretofore described.

It will be clear from the diagrammatic showing of Fig. 17 that when the solenoid is energized the green light will be on, thus indicating each time that the solenoid is energized that the machine is operating normally.

We may also provide a red light, which comes on when the solenoid is not energized at the proper time and the main feed clutch is thrown out. Such means includes a switch 247, shown diagrammatically in Fig. 17 and shown more particularly in Figs. 14 and 15. This switch is normally open and comprises a fixed contact 248 and a movable contact 249. As has been heretofore described in connection with Fig. 6, an arm 135 is fixed to the shaft 106 and engages the end of the pin 134, which is spring pressed rearwardly. When the shaft 106 is rocked clockwise as viewed in Fig. 6, and counterclockwise as viewed in Fig. 15, so as to throw out the main feed clutch, the outer end of the pin 134 passes through the opening 133 and engages the movable contact 249, so as to cause it to engage the fixed contact 248 and close the switch 247. Upon reference to Fig. 17 it will be plain that when the switch 247 closes, the red light will come on and indicate that the main feed clutch has been thrown out.

It is to be noted that the dogs, such as 202, are so positioned on the main cam 60 that, during normal operation, the solenoid will be energized just prior to the time each dog 202 engages the roller 203, and preferably the solenoid remains energized until the dog 202 has passed beyond the roller 203. The wiping contact of a work-piece on the contact 242 is of relatively short duration and the solenoid remains energized during such wiping action. The time of engagement of the contacts 230—231 is of considerable duration, and it is for that reason that we prefer to provide a so-called distributor 236, which closes the contacts 234—235 just prior to the time that the dog 202 reaches the roller 203, and as soon as the dog 202 has passed beyond the roller 203, the cam member 235 on the distributor will permit the movable contact 234 to move, so as to open the circuit and deenergize the solenoid, which thus avoids the waste and heating effect incident to maintaining the solenoid energized for long periods.

It will be seen that if anything goes wrong with the functioning of the magazine feed arrangement, the main feed clutch is thrown out and the operator is provided with a signal to indicate that fact. As soon as the condition which caused the throwing out of the main feed clutch is remedied, the latter may be thrown in manually and thereafter, so long as the machine operates normally, the solenoid will be energized at proper points in the cycle of the machine and the feed clutch will not again be thrown out unless something else goes wrong.

No claim is made herein to the magazine feed device nor to the automatic stop mechanism for the machine, such subject matter being claimed in our divisional application, Serial No. 58,132, filed January 8, 1936.

It will be understood, by those skilled in the art, that when the machine is set up the various means for effecting indexing, locking and clamping of the turret tool slide movements, work feeding, chucking, unchucking, etc., will be arranged so as to function at the desired times and in proper sequence during a cycle of the machine.

We have provided a machine having a considerable number of features of novelty, all looking toward accuracy and speed of production, as well as facility of operation and simplicity. We have also provided safety devices to guard against injury to parts should anything go wrong with the feeding of the work pieces.

15. While one preferred form of the invention has been described in considerable detail, it is to be understood that various changes, omissions and additions may be made within the scope of the invention as defined in the appended claims.

20. We claim:

1. In a machine of the character indicated, a frame, an indexable carrier mounted thereon, said carrier having a circumferentially extending keyway groove on the outside thereof intermediate 25 the ends, a key member on said frame and extending circumferentially about said carrier for less than 180° of the circumference thereof, whereby said carrier may be moved transversely of its axis to engage said key and keyway groove for holding said carrier against axial movement on said frame, and means for clamping said carrier to said frame between indexing movements.

2. In a machine of the character indicated, a frame, a carrier indexably mounted thereon, said carrier having a continuous circumferentially extending groove therein, a key on said frame and coacting with said groove for resisting end movement of said carrier on said frame, and a turret clamping band for clamping said turret in indexed position, said band being seated in said groove.

3. In a machine of the character indicated, a frame, and a carrier indexably mounted thereon, said frame and carrier having circumferentially 45 extending contracting means for clamping said carrier in indexed position and means in substantially the same plane with said clamping means for resisting end movement of said carrier on said frame.

50. 4. In a machine of the character indicated, a frame, a carrier indexably mounted thereon, said carrier having a circumferentially extending groove therein, a clamping band within said groove for clamping said carrier in indexed position, resilient means for urging said band into clamping position, and means for positively releasing said clamping band.

55. 5. In a machine of the character indicated, a frame, a carrier indexably mounted thereon, a clamping band for clamping said carrier in indexed position, said band and carrier having interfitting parts for locating the same relatively to each other, resilient means for urging said clamping band into clamping position, and means for positively releasing said clamping band.

60. 6. In a machine of the character indicated, a frame, a carrier indexably mounted thereon, said carrier having a circumferentially extending groove therein, a circumferentially extending key 70 means on said frame and embracing a portion of said carrier for locating the same longitudinally on said frame, and a clamping band engaging within a part of said groove for clamping said carrier in indexed position.

75. 7. In a machine of the character indicated, a

frame, a spindle carrier indexably mounted thereon, a plurality of rotatable spindles carried by said spindle carrier, a tool slide, an actuating rod connected to said slide and extending centrally through said spindle carrier, a sleeve shaft surrounding said actuating rod, said sleeve shaft being rotatably mounted on said spindle carrier and on said frame at spaced apart points, a gear carried by said sleeve shaft and coacting with gears carried by said spindles, said sleeve shaft 10 being extended through said frame, a second gear carried by said sleeve shaft at the extended portion thereof, and means for rotating said last mentioned gear.

8. In a machine of the character indicated, a 15 tool slide, a draw rod for actuating said tool slide, and means for connecting said draw rod and tool slide comprising a pair of nuts threaded on said draw rod, said nuts having gear teeth on their outer sides, and a part of said tool slide 20 having an aperture therein for the insertion of a pinion tool for coaction with the gear teeth on either or both of said nuts, whereby both of said nuts may be simultaneously rotated for adjusting said draw rod and tool slide relatively to each other, and whereby one of said nuts may be actuated independently of the other to lock said tool slide in adjusted position.

9. In a device of the character indicated, a 30 threaded rod, a member to be secured thereto, and a pair of nuts threaded onto said rod and engaging opposite sides of a part of said member, said nuts being selectively and collectively engageable by a tool whereby both may be actuated simultaneously for adjusting said member on said 35 rod and whereby one of said nuts may be actuated independently of the other for locking said member on said rod in adjusted position.

10. In a device of the character indicated for securing one member to another, one of said 40 members having a pair of screw threaded devices in screw threaded engagement therewith, each of said devices engaging abutment surfaces of the other of said members, said screw threaded devices being selectively and collectively engageable by a tool whereby both may be rotated simultaneously to adjust one of said members relatively to the other and one of said devices may be independently actuated to lock said two members to each other.

11. In a device of the character indicated, a 45 tool slide guide, a tool slide slidable thereon, an actuating rod connected to a part of said tool slide for actuating the latter, a pair of nuts screw threaded onto said rod and engaging opposite sides of a part of said tool slide, said nuts having gear teeth thereon, whereby the gear teeth on each of said nuts may be selectively or collectively engaged by teeth on a pinion tool so as 60 to rotate both of said nuts together to adjust said rod relatively to said tool slide, and whereby one of said nuts may be rotated independently of the other to lock said rod and tool slide to each other.

12. In a device of the character indicated, a 65 tool slide guide, a tool slide slidable thereon, an actuating rod connected to said tool slide for actuating the latter, said rod having a pair of nuts in screw threaded engagement therewith, and engaging opposite sides of a part of said tool slide, 70 said nuts having teeth thereon and said tool slide having an opening therein in open communication with the zone adjacent the teeth at one side of each of said nuts, whereby a pinion may be passed into said opening and be engageable 75

selectively or collectively with the teeth on said nuts for the purpose described.

13. In a machine of the character indicated, a frame, a carrier mounted thereon, a plurality of chucking devices carried by said carrier, means for normally preventing access to said chucking devices from the exterior of said frame, said means being shiftable to permit access to said chucking devices, a drive clutch, and means for preventing said drive clutch from being thrown in while said first mentioned means is in position to permit access to said chucking devices.

14. In a machine of the character indicated, a frame, a carrier, a plurality of chucking devices for said carrier, closure means for normally preventing access to said chucking devices from the exterior of said frame, said closure means being shiftable to permit access to said chucking devices, a feed clutch, and means for preventing said feed clutch from being thrown in when said closure means is in position to permit access to said chucking devices.

15. In a machine of the character indicated, a frame, a plurality of devices, closure means for normally preventing access to said devices from the exterior of said frame, said frame and said closure means having apertures which register with each other when said closure means is shifted to one position, whereby said devices are accessible from the exterior of said frame.

16. In a machine of the character indicated, a frame, a plurality of chucking devices, a closure plate shiftable to different positions on said frame, said closure plate having apertures, and said frame having apertures registering with the apertures in said closure plate when the latter is in one position, whereby access to said chucking devices is permitted.

17. In a device of the character indicated, a frame, a plurality of chucking devices, a closure plate for normally rendering parts of said chucking devices inaccessible from the exterior of said frame, said closure plate and frame being relatively shiftable and having openings which register with said parts when shifted to one position, whereby access to said parts of said chucking devices may be had.

18. In a device of the character indicated, a frame, a plurality of chucking devices, a closure means for normally concealing parts of said chucking mechanism, said frame and closure means being relatively shiftable and having registering openings when said parts are shifted to one position, said openings being sufficient in size to permit withdrawal therethrough of parts of said chucking mechanism.

19. In a device of the character indicated, a frame, a plurality of chucking devices, a closure means for normally concealing parts of said chucking devices, said frame and closure means being relatively shiftable and having registering openings when said parts are shifted to one position, said openings being sufficient in size to permit withdrawal therethrough of parts of said chucking devices, a drive mechanism, and means for preventing said drive mechanism from being thrown in when the openings of said frame and closure means are in registry.

20. In a device of the character indicated, a carrier, a plurality of chucks carried thereby, spring means for closing said chucks, a rod for opening each of said chucks in opposition to said spring means, and a lost motion connection between said rod and said chuck whereby after said chuck is opened said rod may move independently of said chuck.

21. In a device of the character indicated, an indexable spindle carrier, a plurality of rotatable spindles carried thereby, chucks carried by said spindles, spring means for urging each of said chucks to closed position, means engageable with each spindle as it reaches the loading position and engageable with a part of a chuck actuating means for opening each chuck, whereby longitudinal stresses of chuck opening and closing are confined to each spindle, and cam means for actuating said chuck opening means.

22. In a device of the character indicated, feed mechanism, a feed clutch, hand crank mechanism, a member constantly splined to a part of said feed mechanism and rotatable therewith, said member and hand crank mechanism having a disengageable splined connection, and means for connecting said member and said feed clutch whereby when said feed clutch is thrown out said splined connection between said member and hand crank mechanism will be automatically made.

23. In a device of the character indicated, feed mechanism, a feed clutch, hand crank mechanism, a member constantly splined to a part of said feed mechanism and rotatable therewith, said member and hand crank mechanism having a disengageable splined connection, and means for connecting said member and said feed clutch whereby when said feed clutch is thrown in said splined connection between said member and said hand crank mechanism will be automatically disengaged.
